United States Patent Office

Des. 183,186
Patented July 8, 1958

183,186

RESTAURANT SIGN

William B. Smith, Marietta, Ga., assignor to The Embers,
Inc., Atlanta, Ga., a corporation of Georgia

Application January 3, 1958, Serial No. 49,117

Term of patent 14 years

(Cl. D1—12)

Fig. 2 is a rear elevational view thereof; and
Fig. 3 is a top plan view of the same.

I claim:

The ornamental design for a restaurant sign, as shown and described.
